UNITED STATES PATENT OFFICE.

SAMUEL ALLEN GUIBERSON, JR., OF COALINGA, CALIFORNIA.

CASING-ELEVATOR.

1,073,750.

Specification of Letters Patent. Patented Sept. 23, 1913.

Application filed December 23, 1912. Serial No. 738,184.

To all whom it may concern:

Be it known that I, SAMUEL ALLEN GUIBERSON, Jr., a citizen of the United States, residing at Coalinga, in the county of Fresno and State of California, have invented certain new and useful Improvements in Casing-Elevators, of which the following is a specification.

My invention relates to that class of well-casing elevators in which opposing jaw-members adapted to embrace the casing-pipe under its coupling collar are provided at their free ends with an automatic locking means.

The object of my invention is to provide a casing-elevator of this type, the free ends of whose jaw-members are fitted with a simple and effective automatic latch and are formed with interengaging abutments or bearings adapted for stress resistance without undue dependence upon said latch.

To this end my invention consists in the novel casing-elevator which I shall now fully describe by reference to the accompanying drawings, in which—

Figure 1 is a plan of my casing-elevator, showing it locked. Fig. 2 is a front elevation of the same. Fig. 3 is a section on the line $x-x$ of Fig. 1.

1 is one jaw-member of the elevator and 2 is the other jaw-member. These together form the complete embracement for the casing pipe, whether they are symmetrical or complementary, as here shown, or one is of greater arc than the other. These members are hinged together at some point in their joint circumference, whether at or near their suspension lugs 3, or as here shown on a line 4 midway between said lugs.

One of the members, here shown as that designated by 1, has at its free end a projecting flange 5, the inner face of which is formed with a bearing lug 6 projecting from it about midway of its vertical dimension, said lug being best formed tapering as seen in Fig. 2. In the lug 6 is made horizontally a socket 7 in which is seated the latch 8, the beveled head 9 of which is held normally projected from the inner face of the lug, by a spring 10.

11 is a handle, the shank 12 of which is secured to the latch 8, said handle providing the means for manually retracting the latch.

The other member 2 of the elevator has a flange 13 which projects from its free end, and in said flange at its outer end, mid-

way of its vertical dimension, is made a notch 14, the head wall 15 of which is beveled. The notch 14 which is tapered to correspond to the tapered lug 6 is fashioned in size to fit over the said lug 6 of the flange of the opposing jaw member 1, so that the lug will accurately enter and seat itself in the notch regardless of any play in the hinge connection of the jaw members. It will now be seen that when the free ends of the two jaws are brought together, the beveled head wall 15 of the notch 14 acting upon the beveled head 9 of the retractable latch 8 will force said latch outwardly from the path of movement, and when the flange 13 is brought home against the opposing flange 5, the latch 8 will, under its spring 10, move inward again to a locking position behind and against the outer face of the flange 13. The two jaw-members are thus locked together, and in this position their abutments or bearings are, first, the latch on one side and the inner faces of the two flanges 13 and 5 on the other side to lock against so swinging movement about the hinge line 4, and, second, the upper and lower walls of the notch 14 against the upper and lower surfaces, respectively, of the lug 6, to lock the parts against vertical movement. Thus a complete interfitting is provided, locking the parts against movement in any direction and the locking is automatic. In the direction of greatest stress in the use of the elevator, namely, vertical, when lifting the casing section from the ground and lowering it into the well, the strain is not imposed upon the latch, such stress being borne by the interengaging lug 6 and notch 14. To unlock the elevator the latch is retracted by pulling out on the handle 11, whereupon the jaw-members 1 and 2 may be swung open.

I claim:

1. In a casing-elevator the combination of opposing jaw-members hinged together at one end, the free end of one of said members having an outwardly extending flange, the inner face of which intermediate its upper and lower edges is provided with a projecting lug, said lug having a socket made in it parallel with its end face, and the free end of the other member having an outwardly extending flange formed with a notch in its outer end adapted to fit above and below the lug of the first member flange; and a retractable spring controlled latch mounted in
